UNITED STATES PATENT OFFICE

ABRAM LOUIS JEANNERET, OF LA CHAUX-DE-FONDS, SWITZERLAND, ASSIGNOR TO
COMPTOIR GENERAL DE VENTE DE LA MONTRE ROSKOFF SOCIETE ANONYME
VVE. CHS. LEON SCHMID & CIE., OF LA CHAUX-DE-FONDS, SWITZERLAND

LIGHTING DEVICE FOR KEY RINGS

Application filed November 26, 1928, Serial No. 321,984, and in Switzerland April 25, 1928.

The present invention relates to a lighting device such as a luminous watch in combination with a key ring. It is the object of the present invention to combine in one single body the advantages of a luminous watch and of a ring available for holding a bunch of keys. The device is intended for lighting the key hole in the dark when the key has to be introduced.

10 The invention consists in that the watch is arranged in the middle of the ring of a key bunch said ring made in two parts being hinged to the watch-case and being kept closed by a device likewise provided on said watch-case.

15 The annexed drawings represent as an example three working forms of the object of the invention.

20 The Figure 1 is a front view partly in section showing with mixed lines the open position of the arms of the ring.

25 The Figure 2 represents at an enlarged scale a section of the pendant of the watch.

The Figure 3 shows the manner of working 30 of one form of the invention.

The Figure 4 is a front elevation of a second working form.

35 The Figure 5 is a side elevation of the same showing the locking device in section and the ring closed.

The Figure 6 shows the same piece with the 40 opened ring.

The Figure 7 is an enlarged sectional view 45 according to line VII—VII of the Figure 4, and

The Figure 8 is a third working form.

According to the Figures 1 to 3 the watch-case *a* is provided diametrically opposite to the pendant with a lug *b* to which are hinged 50 two arms *c*, forming two halves of the key ring. A leaf spring *d* tends to maintain the arms in their open position. There are notches *e* made at the free ends of said arms and hooks *f*, hinged at *g* on a flanged part of the pendant *h* of the watch.

These two hooks are swingingly arranged within the same plane parallel to the dial. Their tail ends *i* (Fig. 2) are pressed upon by a helical spring *k* for the purpose of keeping the hook ends *f* always engaged in the

notches *e* of the arms *c*. A washer *l* on the stem of the watch rests on the tail ends *i* of the hooks and is in reach of the pins *m* of the pusher knob *n* mounted in the pendant.

When pressing on the knob *n* in the closed position of the ring the hooks *f* will be withdrawn from the notches *e* and the spring *d* will bring the arms *c* into their open position indicated by the mixed lines in Figure 1. Now the keys may be put on.

60 The watch is provided either with a luminous dial or a luminous bottom lined with a phosphorescent matter so that when the watch is brought near a lock as shown in the Figure 3 a beam of light will light up the key 65 hole and facilitate the introducing of the key.

The ring shown here in two pieces could also be in one piece. The parts held in the lug *b* would be one straight piece held swingingly and perpendicularly to the plane of the watch dial. The locking could be made like that in Figure 1 and the hooks would be arranged so as to work in planes perpendicular to the plane of the dial.

70 In the working form of the figures 4 to 7 there is only one arm *c* shaped like a stirrup and hinged with one leg to the watch-case *a* by means of a hinge *o* the axis of which is tangential to the bezel. The other leg is held 75 by a clasp *p*¹ mounted on a lug *p* by means of an axle pin *p*². A spring *p*³ is wound around said pin and is resting with one leg on the clasp *p*¹ and with the other on the arm *c*.

80 The clasp is opened by pressing as indicated in Fig. 6 by the arrow on one wing of the clasp. Then the clasp will be disengaged from its hold on the arm *c* and this arm will be pushed by spring *p*³ into the position shown in Figure 6.

85 In the working form of the Figure 8 the arm *c* is oval-shaped and is surrounding the watch. It is open on one long side. With its other side it is hinged to the watch-case *a*. The ends of the open side of the oval are 90 caught in a clasp *p*¹ which is of a similar arrangement as that shown in the Figures 4 to 7.

What I claim as new is:

1. The combination of a key ring and a

lighting device for the same, comprising a key ring made in two halves, a watch case having a luminous surface arranged inside of said ring, a pendant with a flanged part, a
5 lug on the opposite side of the bezel as support for the hinges at the ends of the halves of the ring, two tailed hooks pivoted on the flanged part of the pendant, a helical spring on the stem and inserted between the tail
10 ends of the hooks and the bezel and adapted to press the said tail ends against the bottom of the pendant, a pusher knob carrying two pins mounted slidably in the pendant and a washer inserted on the underside of the pendant
15 between said pins and the tail ends of said hooks, notches provided at the free ends of the two halves of the ring, said notches engaged by said hooks forming the locking means of the ring, and a leaf spring held in
20 said lug and bearing with its ends on the hinged ends of the ring and adapted to open the latter when the knob is pressed down.

2. The combination of a key ring and a lighting device for the same, said combination comprising a watch having a luminous surface, a ring concentric to said watch, means for attaching said ring to the bezel in spaced relation to the watch case, said means consisting of a hinged part and a detachable part
25 30 for said ring.

In testimony whereof I affix my signature.
ABRAM LOUIS JEANNERET.
